UNITED STATES PATENT OFFICE

CLAUDE SAUZEDDE, OF DETROIT, MICHIGAN

METHOD OF MAKING WHEEL RIMS

Application filed April 8, 1929. Serial No. 353,373.

The present invention pertains to a novel method of making rims for aeroplane and automobile wheels, and the principal object of the invention is to provide an inexpensive and efficient method to obtain maximum rigidity and strength with a minimum of metal to such an extent that a given strength may be increased more than double with half the amount of metal ordinarily required for such strength. A further object is to construct the rim from a blank of metal in such a manner as to provide a seamless structure.

These objects are accomplished by starting with a flat, annular disk, or a simple disk punched to an annular shape, and performing rolling, spinning or pressing operations thereon until the required rim structure is obtained. Preferably, the first operation is performed on the inner circumference of the disk to form an upstanding boss perpendicular to the original plane of the disk by pressing in dies. The free end of the boss is then turned out to form a flange parallel to the remaining portion of the original disk. The flange and disk portions are then turned back to form the usual curled edges, and the boss proper is shaped to conform with the particular requirements of construction or design.

The invention is fully disclosed by way of example in the following description and in the accompanying drawings, in which—

Figure 1 is a fragmentary plan view of the disk;

Fig. 2 is a side elevation thereof after the boss has been formed;

Fig. 3 is a fragmentary section showing the flange formed on the boss;

Fig. 4 is a similar section showing the edges of the material partly shaped;

Fig. 5 is a section of the rim with the edges curled back;

Fig. 6 is a similar section showing a further shaping of the boss proper;

Fig. 7 is a detailed section of the rim, showing the nipple seats formed therein;

Fig. 8 is a detailed developed plan view of the rim;

Fig. 9 is a diametrical sectional view of the

completed rim with the nipple seats formed therein; and

Fig. 10 is a side elevation of the assembled wheel.

Reference to these views will now be had by use of like characters which are employed to designate corresponding parts throughout.

As shown in Fig. 1, there is provided an annular disk 1 of metal such as duralumin or any other suitable material. In view of the operations to be performed on the disk, it is preferred that the inner circumference 2 thereof be comparatively large so that the difference between it and the outer circumference 3 will be in the nature of an increment rather than a multiple.

The disk is treated at the inner circumference to form an up-standing boss 4 perpendicular to the original plane of the disk and retaining a comparatively short flat ring 5 in said plane. The free end of the boss is then turned outwardly to form a flange 6 preferably of the same size as the ring 5.

By means of a suitable rolling or pressing operation or any other method of forming, the straight portion of the boss 4 is bent inwardly or outwardly as at 7 near the edges thereof, and the parts 5 and 6 are bent to provide each an arcuate cross section 8 terminating in a straight lip 9. The curled parts 8 are further compressed until the lips 9 are in surface engagement with the straight portion of the boss, whereby curled rim edges 10 are formed as shown in Fig. 5. The straight portion of the boss is then depressed centrally as at 11, or otherwise shaped in accordance with the particular requirements of structure or design. The two-ply areas formed by the lips 9 in engagement with straight parts of the central boss are cupped or depressed at intervals as at 12 and punched at 13 to form nipple seats, or provision for other fastening means, according to the style of wheel into which the rim is to be assembled.

In the assembly of the wheel, spokes 14 have one end secured to a hub member 15 and the remaining end threaded into a nipple 16 mounted in the corresponding seat. Each nipple has a screw head 17 where-

by it may be turned by means of a screw driver to draw up the spoke with which it is engaged. The inner end of the nipple is formed with facets for engagement by a tool 5 in order to release or further tighten the nipple with respect to the spoke. A screw or rivet would be used instead of a nipple for a disk wheel, but in all cases the nipple or other fastening element serves to hold the edge 9 10 of the curled lip tight against the body of the rim.

The various operations performed in shaping the metal may be accomplished by rolling, spinning or similar processes. It will 15 be seen that the resulting product is entirely unitary, having no seams or joints of any nature, and may be formed to any desired size or shape determined by the size of the original blank and the form of the shaping 20 tools.

Although a specific embodiment of the invention has been illustrated and described, it will be understood that various alterations 25 in the details of construction may be made without departing from the scope of the invention as indicated by the appended claims.

What I claim is:—

1. A method of making a wheel rim consisting in forming a central boss in a disk of 30 metal and retaining a flat ring in the original plane of said disk, flanging the free end of said boss, and shaping said ring and flange into curled rim edges.

2. A method of making a wheel rim consisting, in forming in a disk of metal, a central boss perpendicular to the original plane of the disk and leaving a flat ring in said disk, flanging the free end of said boss, and shaping said ring and flange into curled rim 40 edges.

3. A method of making a wheel rim consisting in forming in a disk of metal, a central boss perpendicular to the original plane of the disk and leaving a flat ring in said disk, flanging the free end of said boss into a plane 45 parallel to the plane of said ring.

4. A method of making a wheel rim consisting in forming a central boss in a disk of metal and retaining a flat ring in the original 50 plane of said disk, flanging the free end of said boss, and shaping said ring and flange into curled rim edges, lapping the marginal portions of said ring and flange into surface engagement with said boss to form areas 55 of two-ply metal, and forming seats for securing elements in said areas.

5. A method of making a wheel rim consisting in forming a central boss in a disk of metal and retaining a flat ring in the original 60 plane of said disk, flanging the free end of said boss, and shaping said ring and flange into curled rim edges, lapping the marginal portions of said ring and flange into surface engagement with said boss to form areas of 65 two-ply metal, and depressing said areas at

intervals to form seats for securing elements.

6. A method of making a wheel rim consisting, in forming in a disk of metal, a central boss perpendicular to the original plane of the disk and leaving a ring in said disk, 70 forming a flange from said boss, shaping said ring and flange into curled rim edges, and lapping the marginal portions of said ring and flange into surface engagement with said boss to form areas of two-ply metal, suitable 75 for use in forming seats for securing elements for said rim.

7. A method of making a wheel rim consisting, in forming in a disk of metal, a central boss perpendicular to the original plane 80 of the disk and leaving a flat ring in said disk, flanging the free end of said boss into a plane parallel to the plane of said ring, and shaping said ring and flange into curled rim edges, lapping the marginal portions of said 85 ring and flange into surface engagement with said boss to form areas of two-ply metal, and depressing said areas at intervals to form seats for securing elements.

In testimony whereof I affix my signature. 90
CLAUDE SAUZEDDE.
